LEVELING MEANS FOR RAILWAY CARS.

Application filed January 26, 1926. Serial No. 83,796.

This invention relates, generally, to improvements in railway cars; and, the present invention has reference, more particularly, to a novel means applicable to the trucks upon which the car-body is mounted, such means serving to maintain the body of the car on a level or horizontal plane, while rounding curves.

The present invention has for its principal object to provide a novel and simple construction, as well as an effectively operating means for use with railway trucks of the six wheel type, for maintaining the body of the car in a level or horizontal plane, while rounding curves, whether right or left-hand curves, with a view of providing comfortable riding, preventing the likelihood of passengers being thrown from the upper berths of sleeping cars; and, furthermore, to prevent spilling or slopping over of food from dishes placed upon the tables of dining cars; and, generally, to prevent accidental movement of merchandise handled in cars, when a train is moving with great speed over a curve.

Other objects of the present invention not at this time more particularly enumerated will be more fully understood from the following detailed description of the present invention.

With the various objects of the present invention in view, the said invention consists, primarily, in a novel means for maintaining the bodies of railway cars in a horizontal or level relation when rounding curves; and, the invention consists, furthermore, in the general arrangements and combinations of the several devices and parts, interposed between the trucks and the body of a railway car, comprising wedge-shaped or inclined elements longitudinally arranged in pairs at the sides of each six wheel truck over the center wheels thereof, and movably or slidably disposed upon each other, whereby the motion between the trucks and the body of the car is compensated for, when rounding curves, in such a manner, that the body of the car will always maintain a horizontal or level relation.

The invention is fully illustrated in the accompanying drawings, in which:—

Figure 1 is a side elevation of the two six-wheel trucks of a railway car, and a fragmentary portion of the body of the car mounted upon said trucks, said view illustrating an embodiment of the principles of the present invention, and the members of the leveling means being represented in their normal initial relation to each other, when the car is travelling upon a straight rail, in the direction indicated by the arrow *x*; Figure 2 is an end view of one of the trucks and fragmentary portion of the car-body; and Figure 3 is a plan or top view of one of the trucks.

Figure 4 is a view similar to Figure 1, showing the relative positions of the trucks to the car-body, when rounding a left-hand curve, and when travelling in the same direction as in Figure 1, indicated by the arrow *y* in said Figure 4.

Figure 5 is a diagrammatic view of one of the trucks and car-body, looking in the direction of the arrow 5 in said Figure 4; and Figure 6 is a similar view of parts of the other truck and car-body, looking in the direction of the arrow 6 in said Figure 4.

Figure 7 is another view similar to Figure 1, showing the relative positions of the trucks to the car-body, when rounding a right-hand curve, and when travelling in the same direction as in Figure 1, indicated by the arrow *z* in said Figure 7.

Figure 8 is a diagrammatic view of parts of one of the trucks and car-body, looking in the direction of the arrow 8 in said Figure 7; and Figure 9 is a similar view of parts of the other truck and car-body, looking in the direction of the arrow 9 in said Figure 7.

Similar characters of reference are employed in all of the said above described views, to indicate corresponding parts.

Referring now to the several figures of the drawings, the reference-character 10 indicates a fragmentary portion of the body of a railway car, and 11 and 12 are the usual six-wheel trucks having a swinging relation horizontally to the body of the car, 100

by means of the usual king-pin connections 13, represented in Figure 2 of the drawings. Upon each outer end-portion of the usual central cross-member 14 of the truck 11 are 5 wedge-shaped block-members 15, the truck 12 being likewise provided upon each outer end-portion of its central cross-member 16 with wedge-shaped block-members 17. As shown in Figures 1, 4 and 7 of the drawings, the upper tapered surfaces 18 and 19 of the respective block-members 15 and 17 incline in downward directions toward each other and toward the middle of the car-body. Suitably secured to the lower timber or 10 flooring of the car-body, in proper locations near the respective sides of the car-body, so as to correspond in position to the respective block-members 15 and 17 of the trucks 11 and 12, are other wedge-shaped block-members 20 and 21, the lower tapered surfaces 22 and 23 of the said respective block-members 20 and 21 inclining in directions away from each other and toward the respective ends of the body of the car, substantially 15 as shown, and the inclined surfaces 22 and 23 of the respective block-members 20 and 21, being adapted to ride directly upon the respective inclined surfaces 18 and 19 of the respective block-members 15 and 17.

30 The operation of these wedge-shaped leveling devices, briefly, is as follows:—

When the car is travelling upon a straight track, the respective block-members 15 and 20, and 17 and 21 are in the relative positions represented in Figure 1 of the drawings, maintaining the body of the car in a horizontal or level position, as will be evident. However, when rounding a left-hand curve, the swinging of the trucks 11 and 12 in the directions of the arrows *s* and *t*, see Figure 4 of the drawings, due to the curves in the rails of the track, thus cause the respective block-members 15 and 20, and 17 and 21, to assume the relative positions represented in 35 Figures 4, 5 and 6 of the drawings, and no matter what the degree of curvature of the rails, or their inclination toward each other, the result will be that the body of the car still maintains its horizontal or level relation. In like manner, when rounding a 40 right-hand curve, the swinging of the trucks in the directions of the arrows *u* and *v*, see Figure 7 of the drawings, due to the curves in the rails of the trucks, will cause the respective block-members 15 and 20, and 17 and 21, to assume the relative positions represented in Figures 7, 8 and 9 of the drawings, and as in the afore-stated case, no matter what the degree of the curvature of the 45 rails, or their inclination toward each other, the result in this instance will also be that the body of the car constantly maintains its horizontal or level relation.

60 From the foregoing description of the present invention it will be seen, that by the arrangement of the wedge-shaped devices or members placed at the outer sides of the trucks above and preferably outwardly beyond the center wheels and at the sides of the car-body, near the end-portions of the latter, we have provided a simply constructed and efficiently operating means for at all times maintaining the body of the car in a horizontal or level relation, irrespective of the degrees of curvature and inclination of 65 the rails, and irrespective of the speed at which the train is travelling.

70 Of course, we are aware that the invention is capable of some changes in the general arrangements and combinations of the several devices and parts, without departing from the scope of the present invention as set forth in the foregoing specification, and as defined in the clauses of the claims which are appended thereto. Hence, we do not 75 limit our invention to the exact arrangements and combinations of the several devices and parts as described in the said specification, nor do we confine ourselves to the exact details of the construction of the said parts, as illustrated in the accompanying drawings.

76 We claim:—

1. In a railway car, in combination with the body of the car and the trucks thereof, wedge-shaped means mounted upon said trucks parallel to the longitudinal axis of the car body, and wedge-shaped means depending from the body of the car also parallel to the longitudinal axis of the car body, the inclined surfaces of said latter means being in slidably relation with the inclined surfaces of the wedge-shaped means of the trucks for maintaining a level relation of the car-body when rounding curves. 95

100 2. In a railway car, in combination with the body of the car and the trucks thereof, wedge-shaped means mounted upon said trucks parallel to the longitudinal axis of the car body, the tapered surfaces of said longitudinally opposed wedge-shaped means upon the respective trucks including downwardly toward each other, and wedge-shaped means depending from the body of the car near the ends thereof, the tapered surfaces of 105 said latter means inclining upwardly in directions toward the respective end-portions of the body of the car and being, respectively, slidably disposed upon the inclined surfaces of the wedge-shaped means of the respective trucks for maintaining a level relation of the car-body when rounding curves. 110

115 3. In a railway car, in combination with the body of the car and the trucks thereof, wedge-shaped means mounted upon and at the end-portions of the cross-beams of the respective trucks parallel to the longitudinal axis of the car body, the tapered surfaces of 120 said longitudinally opposite wedge-shaped 125

130

means upon the respective trucks inclining downwardly toward each other, and wedge-shaped means depending from the body of the car at the sides and near the ends thereof, 5 the tapered surfaces of said latter means inclining upwardly in directions toward the respective end-portions of the body of the car and being, respectively, slidably disposed upon the inclined surfaces of the wedge-

shaped means of the respective trucks for 10 maintaining a level relation of the car-body when rounding curves.

In testimony that we claim the invention set forth above we have hereunto set our hands this 22nd day of January, 1926.

CHARLES P. KNOX.
IRVIN SIMONS.
